LOAD CARRYING SCRAPER

Ivan H. Brown and George S. Allin,
Seattle, Wash.

Application December 23, 1942, Serial No. 469,874

2 Claims. (Cl. 37—126)

This invention relates to improvements in dirt moving vehicles, and it has reference more particularly to improvements in wheel equipped, dirt hauling scrapers of those types referred to, described and illustrated in U. S. Patent No. 2,271,790, issued to George S. Allin on February 3, 1942.

More specifically stated, the present invention relates to the provision of means for the control and operation of scrapers of those types referred to by means of cables and in the provision of a novel arrangement of linkage operatively connecting the scraper gate with a load ejector whereby the movements of the ejector are determined by certain opening and closing movements of the gate.

Explanatory to the objects and advantages of the present invention, it will here be stated that a load carrying scraper of the kind referred to, or one of the type described and illustrated in the patent above mentioned comprises, in general, a dirt containing bowl that is supported between forward and rearward sets of ground wheels and the vehicle equipped with means whereby it is adapted to be drawn by a tractor, or the like to fill the bowl, to transport the load or to perform a leveling off operation. Furthermore, the bowl comprises spaced, opposite side walls, and a back wall, but is open at the front end and bottom. The back wall is fixed between the rearward end portions of the side walls in a rearwardly and upwardly sloping position, and is equipped at its lower edge with a blade for digging into or scraping up of dirt to fill the bowl when the latter is lowered to such position that the blade will be disposed in ground contact. Also, in such scrapers, a gate is supported between the side walls of the bowl, forwardly of the blade, to swing upwardly and downwardly about a horizontal, transverse axis, and is so positioned forwardly of the blade that it may be raised to an open position, thus giving an obstructed entry of dirt to the bowl, and may be closed downwardly from a raised, or open position, first to pick up any run of loose material formed ahead of the blade during a scraping or bowl filling operation and then, when fully closed, to retain the load in the bowl for transportation to a point of discharge.

In the above type of scraper, provision is made that, with the opening of the gate, dry dirt or sand will be automatically discharged by gravity flow. In the event that the material of the load should be wet or muddy and gravity discharge retarded or not possible, the load is then ejected by mechanically actuated means.

In the scraper of the patent above referred to, an ejector plate or shoe is provided at the rear of the bowl. Connected with this plate is a hydraulically operated mechanism whereby the plate may be actuated forwardly against the load for a quick, positive and complete ejection thereof. Also, it has been shown in the scraper of the patent that the scraper bowl may be lifted from and lowered to scraping and loading positions by power that is applied through hydraulic jacks to the mounting frames for the rear sets of supporting wheels.

In the operation of scrapers of this kind, it is most generally the case that tractors of the crawler type are used to draw them. Such tractors are sometimes equipped with cable winding drums adapted for scraper and other auxiliary equipment uses. Therefore, it is frequently more practical that the scraper drawn by the tractor should be cable controlled from the tractor rather than operated under control of hydraulically powered devices on the scraper. Furthermore, under certain climatic conditions, such as hot desert regions, cable operation and control is more practicable from the standpoint of upkeep than is hydraulic equipment.

In view of the foregoing, it has been the principal object of this invention to provide for the control and operation of scrapers of those types or kinds referred to or illustrated in the patent previously mentioned, by cables in lieu of hydraulic power devices.

More specifically stated, it is the object of this invention to provide a wheel equipped scraper having a vertically swinging gate operated between closed and open positions under cable control, and having a load ejector that is operated by and in accordance with movements of the gate.

A further object of the invention is to provide means whereby the gate may be opened to an unobstructed loading position without reaction of any kind on the ejector and whereby the opening of the gate beyond this predetermined degree will cause functional action of the ejector to take place, and through which means the weight of the suspended gate, in a closing operation, will return the ejector to its normal position.

It is also an object of this invention to provide a load carrying scraper of the kind stated, having a vertically swinging gate at the front or open end of the bowl, and a load ejection device at the rear end of the bowl. Furthermore, to provide for operation of the gate under cable control and for the mechanical actuation of the ejector through a novel operating linkage between the

gate suspending arms and the ejector operating shaft whereby upon the opening of the gate beyond a predetermined initial interval, the linkage will cause rotative action of the ejector shaft with a resultant operation of the ejector.

Other objects of the invention reside in the novel features of the various parts used in the combination, and in their relationship and mode of operation, as will hereinafter be fully described.

In accomplishing these and other objects of the invention, I have provided the improved details of construction, the preferred forms of which are illustrated in the accompanying drawings, wherein—

Fig. 1 is a side view of a load hauling scraper embodying the cable control and linkage according to the objects of the present invention; the scraper bowl being shown in a lowered position and the gate being indicated as in closed position.

Fig. 2 is an enlarged sectional detail taken on line 2—2 in Fig. 1.

Fig. 3 is a half-top view or plan of the scraper with the gate and ejector set as in Fig. 1.

Fig. 4 is a sectional detail showing the ejector moved forwardly of normal position.

Referring more in detail to the drawings—

Briefly described, the scraper to which the present invention is applied, comprises a bowl for the receiving and transporting of a load of dirt. The bowl is supported between forward and rearward sets of ground wheels and the vehicle thus formed is equipped with a tongue, or draw bar, whereby it may be attached to a tractor or the like. The bowl has a scraper blade fixed across the forward edge of the bottom wall and this, when brought into ground contact by lowering the bowl, will operate to dig up the dirt and cause it to flow into the bowl as the vehicle is moved forwardly. Raising and lowering of the bowl is effected by making downward and upward swinging adjustments of the rear sets of wheels and this movement of the wheels is under control of manually operated mechanism most generally carried on the tractor and easily accessible to the tractor operator.

In the scraper herein illustrated, the bowl is designated in its entirety by reference numeral 1. It comprises the parallel, spaced opposite side walls 2 and 2'. These walls preferably are sheet metal plates of substantial height and length; each plate being equipped with a forward extension frame for support comprising rigid struts 3 and 4, arranged as seen best in Fig. 1. These struts at each side of the bowl have their rearward ends fixed securely to the corresponding side wall plate adjacent top and bottom edges thereof, respectively, and are joined together at their forward ends.

It is observed in Fig. 1 that the upper strut 3 is made up of two parallel, tubular members mounted at their opposite ends in bearing blocks 3a and 3b respectively. In Figs. 1 and 2, it is shown that the block 3b is mounted on a pin 3x that is fixed in and extends outwardly from the side wall plate 2. The block 3a, likewise, is fixed on a pin 3y that is mounted in and extends outwardly from the forward end portion of the strut 4.

As a detail of construction, the side wall plates of the bowl are stiffened by horizontal flange plates 40 welded thereto along their top edges, and in Fig. 5 it is shown that the pin 3x is given additional support by reason of its being fixed in

a depending bracket 41 that is welded to the outer edge of the flange plate 40.

The extension frames that are fixed to the opposite side plates of the bowl are joined rigidly in spaced relationship by a horizontal member 5 which, in this instance, is a heavy tubular beam, as noted in Fig. 4.

It is shown in Figs. 3 and 4 that the upper, forward ends of the strut frames 4 are enlarged to provide for the fixing of the ends of struts 3 thereto and it is to these enlarged upper end portions that the tubular cross beam 5 is welded.

The bowl is supported at its forward end by a gooseneck bracket 6 that is fixed solidly to the beam 5 in the central longitudinal plane of the bowl. This bracket arches upwardly and forwardly, then extends downwardly, and at its lower end it pivotally mounts a knuckle 7 which, in turn, is pivotally mounted on a cross axle 8. The axle 8 is the front axle of the vehicle and is equipped with ground wheels 9—9 at its opposite ends. A draw bar 10 is operatively fixed to this axle as seen in Fig. 3 for connecting the vehicle with a tractor or prime mover.

The forward end of the bowl, that is, the space between the forward end portions of the opposite side wall plates 2 and 2', is open, as is also the bottom of the bowl, except for the gate, as presently will be explained. The rear end of the bowl, that is, the space between the rearward edges of the side wall plates 2 and 2', is permanently closed by a forwardly and downwardly inclined wall 11 which is designated as the "back wall." This back wall is equipped along its lower edge with a scraping blade 12, having its lower cutting edge extended somewhat below the lower edges of the side walls to adapt it for the intended scraping and loading operation.

The back wall 11 is substantially reinforced, and is supported between the side walls by suitable cross beams 13. This wall slopes upwardly and rearwardly from the blade at approximately a 25° angle relative to the ground level, and its top edge terminates approximately midway of the top and bottom edges of the side walls, as will be observed by reference to Fig. 4.

At its rearward end, the bowl is supported for use, transportation and for vertical adjustment by a pair of laterally spaced sets of ground wheels 15—15, mounted at the rearward end of a vertically oscillating frame 16. This frame comprises side arms 16x that extend along sides of the bowl and are pivotally hinged at their ends, as at 17, to the side walls near the pivots 3x. At its rear ends, the frame 16 has laterally extended spindles 20 fixed therein on which the ground wheels 15 are revolvably mounted.

The raising and lowering of the bowl relative to the ground to various positions for loading, leveling off or for transportation of a load, is effected by the relative vertical adjustment of the rear end of the wheel mounting frame 16. This adjustment is accomplished through cable winding mechanism as shown best in Fig. 3, wherein it is seen that a cable 22 leads rearwardly from a winding drum 23 on the tractor, passing beneath and upwardly about a guide sheave 25 mounted on the forward end portion of the gooseneck bracket 6, thence passing upwardly therefrom and over and rearwardly about a sheave 26 mounted on the crown of the gooseneck bracket 6, thence rearwardly along the bracket to a sheave 27, then extended laterally and about a sheave 28 at the side and forward end of the bowl, thence rearwardly along the side wall of the bowl, about

a sheave 28 at the rear, then again inwardly and over a sheave 29, and finally the cable is threaded through pulley blocks indicated at 30 and 31, fixed respectively to the rear end of the bowl and to the rear end portion of the wheel frame 16. The cable 22 may be paid out or drawn in on the winding drum 23 to swing the frame 16 upwardly or downwardly, thus to lower or raise the bowl accordingly, as is well understood in the art.

As will be noted by reference to Fig. 4, the rear wall 11 of the bowl is so inclined that, with the blade 12 moving forward while in digging contact with the ground, there will be a relatively easy digging action and a comparatively easy upflow of earth across the blade, to be pushed up the back wall and retained in the bowl between its opposite side walls as provided for by the gate.

The gate is designated in its entirety by reference numeral 35, and it extends transversely between the opposite side walls of the bowl to serve, when needed, as a closure for the front end and for the open bottom of the bowl when it is desired to retain and transport a load in the bowl. The gate, as shown in Fig. 1, is an angularly formed plate, substantially braced on its forward side and of substantial width from top to bottom edge. This plate is equipped along its longitudinal side edges with load retaining wings 36, and it is supported in the bowl from its opposite side edges by a pair of levers or arms 37 that are welded or otherwise fixed to the wings to extend rearwardly therefrom at the outside of and closely along the side walls of the bowl. Near their rear ends, these levers are pivotally mounted on pivot bolts 38 fixed in the side walls of the bowl near the top edge of the latter, as seen in Fig. 1. Each of the gate supporting lever arms 37 is in the nature of a bell crank lever and has a part 37' extending angularly beyond the pivots 38 and these, as presently described, serve as part of the operating means for the load ejector plate.

Raising and controlled lowering of the gate is effected by means of a cable 45 that is fixed at its lower end to the lower edge portion of the gate, as indicated at 45x in Fig. 1, and extends upwardly from the point of connection with the gate over a sheave wheel 46 that is mounted at the rear of a frame 47 fixed upon the goose-neck bracket 6, then is extended forwardly and is attached to a pulley block 48. An operating cable 49 extends from a winding drum 50 on the tractor, over a fairlead 50' and about sheaves 51 at the forward end of the bracket 6 and about sheaves 52 in the block 48 and is finally dead-ended in the block 48. When cable 49 is wound in on the tractor drum 50, the gate will be raised. When the cable is paid out, the gate will lower under its own weight, to closed position against blade 12.

Filling of the bowl may be accomplished by moving the bowl forwardly while the blade is in ground contact and the gate open.

Assuming the bowl to be raised from the ground, ready to unload, any slight opening of the gate will permit the dirt to spill out, and its rate of spill is in accordance with the extent to which the gate is opened, the elevation of the scraper body and the character of the dirt. For the forcible ejection of a load, the gate would be fully opened and the ejector plate functionally actuated.

The load ejector as here shown comprises a plate 60 that extends between the side walls of the bowl above the back wall 11. Normally, the

lower edge of the plate 60 overlaps the top edge of the back wall 11, resting thereagainst for the support of a load. The ejector plate serves as a continuation of the back wall and it curves upwardly and forwardly as it approaches the top edge of the bowl.

The ejector plate is functionally supported at its opposite side edges by a pair of lever arms 65-66 that are fixed at their lower ends to the opposite end portions of a cross shaft 66 that is horizontally disposed, back of the wall 11 and revolvably contained in suitable bearings in the rear edge portions of the side walls of the bowl. At their upper ends, the arms 65-66 are pivotally fixed as at 68, to the back of the ejector plate near its upper edge.

At its outer ends, the cross shaft 66 has upwardly directed lever arms 70 fixed thereto, and to these arms, at each side of the bowl, are links 71 which extend forwardly and have operating connection with the lever arms 37' of the gate mounting levers 37. It will be noted in Fig. 1 that the connections between the forward end portion of a link 71 and the corresponding lever arm 37' is effected by a pivot bolt 75 in the end of the lever arm, extended through a longitudinal slot 76 in the forward end portion of the link. This "lost motion" connection provides that, with the ejector plate in its retracted, normal position, the gate may be moved from a completely closed position to an open position suitable for loading, without causing action of the ejector. However, upon opening the gate beyond normal loading opening the levers 37' cause pull to be applied through the links 71 on the lever arms 70 to rotatably actuate the shaft 66, thus through the mediacy of the lever arms 65, to swing the top edge of the ejector plate forwardly, then to slide the plate downwardly along the back wall to cause the forcible ejection of the load. After a load has been ejected, the gate may be lowered to closed position, and in this movement, will cause the ejector to be returned to its normal position, resting at its bottom edge against the wall plate 11 and at its top portion against the cross member which joins the side wall plates of the bowl; this being designated at 80 in Fig. 4.

We claim:

1. In a vehicle of the character described, a dirt receiving bowl open at its forward end and equipped with a scraping blade for filling the bowl, a gate for the open end of the bowl, lever arms swingingly mounting the gate on the bowl for swinging movement between fully closed and fully open positions, means for actuating the gate between open and closed positions, an ejector plate movable in the bowl from a retracted position toward the open end of the bowl for the ejection of a load therefrom, a shaft rotatably mounted in the bowl, lever arms fixed to the shaft and pivoted to the ejector plate for the actuation of the latter, crank arms on the shaft ends, links having ends pivotally attached to the crank arms and having pin and slot connection with the gate mounting lever arms; said pin and slot connection providing for an initial opening of the gate for loading the bowl without actuation of the ejector, and for the functional actuation of the ejector incident to moving of the gate from that partially open position for loading, to a full open position.
2. In a vehicle of the character described, a scraper bowl open at its forward side and having opposite side walls and an upwardly and

rearwardly sloping bottom wall, a gate for the open side of the bowl, bell crank levers pivoted on the side walls with ends fixed to the gate to support it for swinging movement between open and closed positions, an ejector plate resting at its lower edge in sliding contact with the bottom wall, a cross shaft revolvably mounted in the bowl back of the ejector plate, lever arms fixed to the cross shaft and pivoted to the ejector plate near its top edge for its support and actuation, operating levers fixed to the cross shaft, links joining the levers with the other arms of

the bell cranks, and including lost motion connections therein whereby the cross shaft will be rotated incident to opening movement of the gate beyond a predetermined partially open position to actuate the ejector downwardly along the bottom wall and whereby the ejector will be retracted with the return of the gate to fully closed position, and means for raising and lowering the gate.
